CONTROL HANDLE FOR AN INDUSTRIAL TRUCK

Rune G. Mono, Taby, Sweden, assignor to AB Bygg-och
Transportekonomi (BT), Bromma, Sweden

Filed Dec. 26, 1972, Ser. No. 318,488

Claims priority, application Sweden July 5, 1972

Term of patent 14 years

Int. Cl. D12—16

U.S. Cl. D12—174

Fig. 1

Fig. 2

Fig 3Fig 4

FIG. 1 is a right front perspective view of a control handle for an industrial truck showing my new design;

FIG. 2 is perspective view taken from the left side thereof;

FIG. 3 is a rear perspective view thereof; and

FIG. 4 is a top plan view thereof to an enlarged scale, with the lower portion of the control handle omitted for convenience of illustration.

I claim:

The ornamental design for a control handle for an industrial truck, as shown.
